UNITED STATES PATENT OFFICE

2,040,402

ELECTRIC CONTROL APPARATUS FOR
FUEL BURNERSLawrence M. Persons, Des Moines, Iowa, assignor
to Penn Electric Switch Co., Des Moines, Iowa,
a corporation of Iowa

Application November 17, 1933, Serial No. 698,478

4 Claims. (Cl. 158—28)

One object of my invention is to provide control apparatus for the electric circuit of a fuel burner, which apparatus is comparatively simple to manufacture and also inexpensive.

5 A further object is to provide an automatic controller including a combustion switch which is opened when combustion occurs in order to break the circuit through a heater of a lock-out switch so that upon combustion occurring the lock-out switch will not thereafter lock out.

Still a further object is to provide control apparatus including a room thermostat operated relay which initiates and terminates operation of a fuel burner and which initiates operation of 15 ignition mechanism for the fuel burner, termination of the operation of the ignition mechanism being effected by an ignition trip mechanism which in turn is operated by the heating of a warp switch when in its hot position, a combustion switch being provided to cause operation of the heater of the warp switch.

A further object is to provide control apparatus including a warp switch operating to terminate the ignition circuit after a time period and to open relay starting holding contacts so that upon flame failure, a purging period is provided before the control apparatus re-initiates operation of the fuel burner by re-engaging said relay starting holding contacts, thus allowing the combustion chamber to be cleared of dangerous gases by the natural draft in the furnace before the ignition mechanism is re-energized and thus eliminating an explosion upon such re-energization.

My control apparatus may be used in connection 35 with a fuel burner for burning oil, gas or other fuel whereby upon combustion failure occurring such as caused by a down-draft in the furnace, a slug of water in the fuel oil or the like, automatic operation of the controller will recycle after a purging period has been provided to allow the draft of the furnace to purge the combustion chamber of any explosive gas caused by the introduction of fuel after combustion fails, or will, after several purging periods, stop the operation 40 of the burner until the same has been remedied and the apparatus reset.

Still another object is to provide in a control apparatus, a combustion switch which opens the initial circuit through a lockout switch heater and closes it through the entire coil of a relay, the lockout switch heater being in circuit with only a part of said coil.

Another object is to provide a control structure 50 in which ignition contacts are normally closed, but the ignition current does not flow through

them until a room thermostat is closed, these contacts being so mounted on a relay that they remain "on" when the relay is energized and ignition trip mechanism being provided for thereafter tripping them to the "off" position.

5 Another object is to provide means for controlling the ignition trip mechanism from a combustion switch, a delayed action mechanism being interposed between the combustion switch and the ignition trip mechanism so that ignition is had over a considerable period of time, this being especially desirable for the rotary types of oil burners requiring a long ignition period for insuring combustion.

Another object is to provide novel controlling 15 mechanism including a relay or the like and a latch means cooperating with parts operated by the armature of the relay to cause certain contacts to remain in their normally relay de-energized position when the relay coil is energized but 20 which will move to their other position when the latch means is released, providing the relay coil is still energized.

With these and other objects in view my invention consists in the construction, arrangement and combination of the various parts of my device, whereby the objects contemplated are attained, as hereinafter more fully set forth, pointed out in my claims, and illustrated in the accompanying drawings, in which:

30 Figure 1 is an electrical diagrammatic view of an electric control apparatus for fuel burners embodying my invention.

Figures 2, 3 and 4 are diagrams of the combustion switch of Figure 1 in different successive positions between the cold and hot positions of the switch.

Figure 5 is a partial view of the relay switch of Figure 1 showing it in energized position.

Figure 6 is a portion of Figure 5 showing an 40 ignition trip mechanism in tripped position.

Figure 7 is a diagram of the warp switch of Figure 1 showing it in an intermediate position.

Figure 8 is a similar view showing it in hot position; and

Figure 9 is a simplified diagrammatic view of the system.

My apparatus includes a combustion switch having a shaft 11 rotated by a bimetal or other type of temperature responsive element 13 and 50 in turn rotating a notched disk 15 with the periphery of which a leaf spring operating arm 17 of the combustion switch coacts. The combustion switch includes starting contacts 10, running holding contacts 12 and warp switch heater initiating 55

contacts 14. The combustion switch operates as disclosed in the Williams Patent No. 1,827,703, issue October 13, 1931.

Operating from the cold position of Figure 1 to the hot position of Figure 4, the contacts 12 are first engaged, as in Figure 2, the contacts 14 are then also engaged as in Figure 3 and lastly the contacts 10 are opened as in Figure 4. The combustion switch when operating from hot to cold position will cause the contacts to successively assume the positions of Figures 4, 3, 2, and 1.

The relay switch of my apparatus includes ignition contacts 16, motor contacts 18 and 20, secondary holding contacts 22 and primary holding contacts 24, all of which are controlled by an armature 19 adapted to be attracted from the normal position of Figure 1 to the energized position of Figure 5 by either one or both coils 26 and 28 of the relay.

20 The relay switch further includes an ignition trip magnet 30, an ignition trip armature 32 which also acts as a contact and a contact 34 cooperating with the armature 32. The contact 34 is carried on a leaf spring 35 with which one of the contacts 16 is connected and an extension 37 connects with a contact carrier 39 on the armature 19.

In my apparatus, I provide a lock-out switch having normally closed contacts 36 adapted to be opened by a cam 38, which in turn is held in its inoperative position by a bimetal latch 40.

The latch 40 is adapted to be warped to unlatching position by a lock-out switch heater 42.

The warp switch of my apparatus comprises a bimetal element 50 for opening normally closed starting contacts 44, normally closed chatter prevention contacts 46 and closing normally open ignition trip contacts 48. A warp switch heater 52 is provided for warping the bimetal element 50 from its normal position of Figure 1 to its hot position of Figure 8.

The ignition mechanism of a fuel burner and the burner motor usually provided for operating a blower are connected in circuit with the lock-out switch and the relay switch through terminals L¹, I, and M. A transformer 9 has its primary connected through the lock-out switch and with a current supply terminal L².

50 The transformer has a secondary winding for supplying current through a room thermostat R. T. connected with terminals R¹ and R² to the warp switch heater 52, lock-out switch heater 42, relay coil 26-28 and ignition trip magnet 30.

55

Practical operation

The circuit connections with the various coils, heaters, contacts, etc. are all fully shown in Figures 1 and 9. The parts are in normal or non-operating position.

60

Starting circuit

When the room thermostat R. T. closes because of lowering of the room temperature to a predetermined degree, a starting circuit is closed (see Figure 9) from one end of the transformer secondary through R. T. and wire a and the coil 28 of the relay switch, through the lock-out switch heater 42, through the wire c, bimetal 50 and chatter prevention contacts 46 and through the starting contacts 44 and then through wire d and the starting contacts 10 of the combustion switch and wire e to the other end of the transformer secondary. This causes the armature 19 to be attracted whereupon its contacts 18, 20, 22 and 24 are closed and 16 are urged to open but are held

closed or in their normal position by the ignition trip armature 32 (see Figure 5).

The closing of the contacts 18 and 20 establishes through wires f, g and h both the motor circuit and the ignition circuit from the line through the lock-out switch contacts 36, the ignition contacts 16 being already closed, the motor circuit also including wires i and j and the ignition circuit wires k and l.

Running circuit

10

Energization of the relay coil 28 closes the secondary holding contacts 22 so that the current from the room thermostat can flow through wire a and the entire relay coil 26-28, then through wire m and the contacts 22 and wire n and through the running holding contacts 12 of the combustion switch and then through the wire e if combustion occurs and the switch moves to the position of Figure 2.

This circuit is normally maintained until the room thermostat opens the circuit because of rise of the temperature in the room to a predetermined degree, or in case of a non-normal condition such as combustion failure occurring, the combustion switch will return to the cold position of Figure 1, thus opening the running holding contacts 12 and opening the relay coil circuit through wires a, m, n, and e.

Warp switch circuit

30

If combustion normally occurs, the warp switch heater initiating contacts 14 will close after the contacts 12 close as in Figure 3, thus establishing the circuit from the room thermostat through wires o and p and the warp switch heater 52 and wire q and the combustion switch contacts 14 and 12 and wire e to the upper end of the secondary coil of the transformer.

The warp switch heater 52 will gradually warp the element 50 to the position of Figure 7 and then to the position of Figure 8. In Figure 7, the starting contacts 44 shunting the contacts 24 by wires d, r, and s are opened and so are the chatter prevention contacts 46. In Figure 8, the ignition trip contacts 48 are closed, this occurring a substantial time period after the running holding contacts 12 of the combustion switch are closed and this period of time being provided for continued energization of the ignition to give it plenty of time to cause combustion.

Closing of the contacts 48 establishes a circuit from the room thermostat through wires o and t and the ignition trip magnet 30 and its contacts 32 and 34 and then through wires u and m and 55 the contacts 22 wire n and contacts 12 to the upper end of the secondary coil of the transformer through wire e. Energization of the magnet 30 attracts the armature 32 from the position of Figure 5 to the position of Figure 6 and 60 in so doing, the contacts 32 and 34 are separated so that current flows only momentarily through the magnet 30 and the switch blade 35 springs upwardly to separate the ignition contacts 16. This de-energizes the ignition mechanism.

If combustion does not occur in the ordinary manner, the combustion switch will remain in the position of Figure 1 and current will continue to flow through the lock-out switch heater 42, coming through the relay coil 28 and passing through the contacts 46, 44 and 10 and through wires a, b, c, d, and e. After a time period, the latch 40 will release the cam 38 for opening the contacts 36 and thus shutting off the current supply and shutting down operation of 75

the control apparatus until the trouble is remedied and the lock-out switch manually reset.

In case of failure of combustion after it once occurs however, it is desirable to provide a purging period during which gases in the furnace can be purged therefrom by the natural draft and then have the control apparatus re-cycle for attempting another start as for instance when there is a down draft through the furnace or a slug 5 of water in the fuel oil, the burner may be able to operate normally after a purging period. If more than two or three of these purging periods occur however, it would undoubtedly be due to some trouble that could not be remedied by a 10 purging period, whereupon the successive heatings of the lock-out switch heater 42 would trip the lock-out switch.

For the purging period, the combustion switch would return from the position of Figure 4 to 20 the position of Figure 1. When it assumed the position of Figure 3, the contacts 10 would be closed so that the starting circuit through the relay coil 28 can be re-established at the proper time. When the position of Figure 2 is assumed, 25 the contacts 14 open for de-energizing the warp switch heater 52. In the position of Figure 1, the contacts 12 open for thus opening the circuit through the relay and shutting down the operation of the burner motor.

30 The bimetal element 50 will now slowly move from the position of Figure 8 to the position of Figure 1 due to de-energization of the heater 52 and provide, during the time of such movement, the desired purging period. At first, the contacts 35 48 will be separated so they will be in position for initial operation and then the contacts 46 will close so that they also will be in position for initial operation and the tension of the leaf spring between the contacts 44 and 46 will be 40 imposed on the bimetal 50 to dampen any tendency of it to vibrate.

When the contacts 44 then close they will do so without chattering due to such tension and the purging period is ended and the starting circuit is re-established through wires a, b, c, d, and 45 e, as already described.

It will be noted that the starting circuit is not re-established until both the chatter prevention contacts 46 and the starting contacts 44 of 50 the warp switch are closed. The progressive movement of the bimetal element 50 of the warp switch during the cooling period is not necessarily smooth and if the contacts 44 only were provided, there would be a possibility of chattering 55 in the starting circuit when they were closed. With the contacts 46 in series with them however, the contacts 46 are first closed and then the contacts 44 (which shunt the normally open primary holding contacts 24 of the relay switch) 60 are closed, immediately causing the contacts 24 to close because of energization of the starting coil 28 of the relay switch.

The ignition trip contacts 48 for controlling the ignition trip magnet 38 may be dispensed 65 with where only a short ignition period is required, such as disclosed in my copending application, Serial No. 698,477, filed November 17, 1933. In the present application, the contacts 48 are used and closed after a delayed period of 70 time by the bimetal element 50 of the warp switch so that a long ignition period is obtained.

Especially in the rotary types of burners where initiation of combustion is slow, an extended ignition period as accomplished by my present circuit is desirable.

With respect to the contacts 18 and 20, either of these can be dispensed with because they are in series and control the motor. The two of them are used merely so that the jumper 39 can be used instead of a single set of contacts and pigtail connections. This does away with connections of this character which are not entirely satisfactory.

Although I have shown the latch 32 associated in a fuel burner control apparatus, it is obvious 10 that this same latch can be associated with any kind of relay or the like to retain certain contacts in the position they normally assume when the relay coil is de-energized and permit these contacts to move to their other position when the 15 latch 32 is actuated. This is a novel construction which can be used in many circuit installations other than the illustrative one of Figure 1.

Some changes may be made in the construction and arrangement of the parts of my device without departing from the real spirit and purpose of 20 my invention, and it is my intention to cover by my claims, any modified forms of structure or use of mechanical equivalents, which may be reasonably included within their scope. 25

I claim as my invention:

1. In a control system for a fuel burner and its fuel feeding means, a control circuit including an igniter, a motor controlling fuel feed, a multiple contact relay operable when energized 30 to close contacts energizing said motor and igniter and to close primary and secondary holding contacts in series with the coil of said relay, an electrically actuated thermal warp switch having contacts which are closed when the thermal 35 warp element is cold shunting said primary holding contacts to permit a starting circuit to be established while they are open, a combustion switch having first contacts operable to establish a circuit through said secondary holding contacts and having second contacts to energize said 40 warp switch upon combustion occurring, whereupon after a time period the contacts of the warp switch are opened and the relay coil is maintained energized through said secondary holding contacts and said first contacts, said combustion switch upon combustion failure de-energizing said warp switch by opening said second contacts and opens said circuit established by said first contacts and including said secondary holding contacts 45 whereby said relay is de-energized and said warp switch, after providing a purging period while it is cooling down and upon reclosing its contacts will re-establish the circuit around said primary holding contacts to cause re-cycling of 50 said control system.

2. In a control system for a fuel burner and its fuel feeding means, a control circuit including an igniter, a motor controlling fuel feed, a multiple contact relay operable when energized to close 60 contacts energizing said motor and igniter and to close holding contacts in series with the coil of said relay, an electrically actuated thermal warp switch having contacts which are closed when the thermal warp element is cold and which 65 shunt said holding contacts to permit a starting circuit to be established while they are open, a combustion switch having first contacts operable to establish a secondary circuit through said relay coil and having second contacts to energize 70 said warp switch upon combustion occurring whereupon after a time period the contacts of the warp switch are opened and the relay coil is maintained energized through said secondary circuit including said first contacts, said combustion 75

switch upon combustion failure de-energizing said warp switch by opening said second contacts and opens said secondary circuit established by said first contacts whereby said relay is de-energized, said warp switch, after providing a purging period while it is cooling down and upon reclosing its contacts will re-establish the circuit around said holding contacts to cause re-cycling of said control system.

10 3. In a control system for a fuel burner and its fuel feeding means, a control circuit including an igniter, a motor controlling fuel feed, a multiple contact relay operable when energized to close contacts energizing said motor and igniter and to urge contacts controlling energization of said igniter which are closed when said relay is de-energized, towards open position, an electrically operable latch mechanism holding said ignition contacts closed when de-energized, said relay also operable when energized to close holding contacts in series with the coil of said relay, an electrically actuated thermal warp switch having contacts which are closed when the thermal warp element is cold and which shunt said holding contacts to permit a starting circuit to be established while they are open, a combustion switch having first contacts operable to establish a secondary circuit through said relay coil and having second contacts to energize said warp switch upon combustion occurring whereupon after a time period the contacts of the warp switch are opened and the relay coil is maintained energized through said secondary circuit including said first contacts, said combustion switch upon combustion failure de-energizing said warp switch by opening said second contacts and opening said secondary circuit established by said first contacts whereby said relay is de-energized, said warp switch, after providing a purging period while it is cooling down and upon reclosing its contacts will re-establish the circuit around said holding contacts to cause re-cycling of said control system, said warp switch also having contacts which are closed upon said warp switch assuming its warped position, said last contacts controlling energization of said latch mechanism.

4. In a control system for a fuel burner and its fuel feeding means, a control circuit including an igniter, a motor controlling fuel feed, an electrically actuated safety switch in said control circuit, a multiple contact relay operable when energized to close contacts energizing said motor and igniter and to urge contacts controlling energization of said igniter which are closed when said relay is de-energized, towards open position, an electrically operable latch mechanism holding 10 said ignition contacts closed when de-energized, said relay also operable when energized to close holding contacts in series with the coil of said relay, an electrically actuated warp switch having contacts which are closed when the thermal warp 15 element is cold and which shunt said holding contacts to permit a starting circuit to be established while they are open, means in circuit with the coil of said relay to open said safety switch after a time period of energization of said means, 20 a combustion switch having first contacts operable to establish a secondary circuit through said relay coil and having second contacts to energize said warp switch upon combustion occurring whereupon after a time period, the contacts of 25 the warp switch are opened and the relay coil is maintained energized through said secondary circuit including said first contacts, said combustion switch having third contacts in series with the coil of said relay and opened upon combustion 30 establishment to terminate energization of said means to open said safety switch, said combustion switch upon combustion failure, de-energizing said warp switch by opening said second contacts and opens said secondary circuit established by 35 said first contacts, whereby said relay is de-energized and said warp switch, provides a purging period while it is cooling down and upon reclosing its contacts will re-establish the circuit around said holding contacts and through said 40 third contacts to cause re-cycling of said control system, said warp switch also having contacts which are closed upon said warp switch assuming its warped position, said last contacts controlling energization of said latch mechanism. 45

LAWRENCE M. PERSONS.
